UNITED STATES PATENT OFFICE.

THOMAS T. TUTTLE, OF HAWLEY, PENNSYLVANIA.

MOVING-PICTURE FILM.

1,261,979.

Specification of Letters Patent.

Patented Apr. 9, 1918.

Application filed December 3, 1914. Serial No. 875,243.

To all whom it may concern:

Be it known that I, THOMAS T. TUTTLE, a citizen of the United States, residing at Hawley, in the county of Wayne and State 5 of Pennsylvania, have invented a certain new and useful Moving-Picture Film, of which the following is a specification.

My invention relates to protections for the edge of a motion picture film to prevent 10 scratching, strengthen the edge against wear and prevent the separation of the parts of the film when the body of the film is torn.

The purpose of my invention is to impregnate the binding material with the material of which the film is composed, thus using the film material as a binder or cement and incorporating each somewhat in the body of the other.

A further purpose of my invention is to 20 so place a fabric edge binder that the threads run "bias", or at an angle with the length of the strip, producing a truss effect and allowing the fabric to yield slightly with stretching of the film.

25 Further purposes of my invention will appear in the specification and claims hereof.

I have preferred to illustrate my invention by one form thereof which is practicable, efficient and inexpensive and which at 30 the same time well illustrates the principles of my invention.

Figure 1 is a plan view of a section of film embodying my invention.

Fig. 2 is a partial section of the structure shown in Fig. 1, taken upon line 2—2 thereof.

In moving picture work the film as constructed has been excessively worn because of the direct wear upon the photographic 40 image surface. Various efforts have been made to avoid this by binding the edge, but without success, owing in part to the objectionable character of the material employed as a binder and in part to the means of attaching the binder to the film.

Since the films are for the most part made of pyroxylin materials which are highly explosive, any stoppage of the film in front of the lens of the projecting apparatus leads 50 to almost immediate fire, ordinarily accompanied by an explosion. My invention is designed to carry the film on, notwithstanding breakage or other cause of retention of the film. At the same time, I have made the 55 border of the film of a flexible and somewhat elastic material incorporated in the

body of the film and yielding longitudinally with the film both because of the elastic character of the threads, but because of the bias or angular relation of the threads to 60 the length of the film.

I prefer to use the ordinary celluloid or other pyroxylin product film. It will be recognized that gelatin and many other gelatinous materials than pyroxylin may be 65 used.

In the drawings the material 5 of the film extends from side to side. Preferably, during the manufacture of the film, a border 6, most desirably of silk, linen or other cloth is 70 attached to the film by the material of the film itself. If applied during the manufacture of the film, the border is pressed into contact with the material of the film before the latter dries, causing the material to enter the interstices between the threads of the fabric and impregnate the adjoining fabric.

75 Where the border is applied subsequent to the manufacture of the film, it is my purpose to soften the film by any suitable solvent and to press the fabric border into the film with the same effect of filling the spaces between the fibers and threads of the fabric and impregnation of the adjoining surface of the fabric as before. Solvents of the various 80 gelatinous substances, including celluloid are well known and need not be detailed here. For the commercial films as now used the so-called "cement" for splicing films may be 85 used.

In either event, it is my purpose to incorporate the materials of the film and border each within the other so intimately that the 90 gelatinous or other materials of the film shall have the advantage of increased frictional grip between them in addition to the hold of the material of the film as an agglutinant.

I recognize that, for the purposes of my invention, the portion of the body of the 100 film which is pressed into the interstices of the film border need not be part of the initial strip which was formed into the film but may be built up upon the sides of the strip by adding material in liquid or nearly 105 liquid form and of such similar character to that of the film as to become, in effect, a part of the body of the film.

In order to get the very best effect from this film border, it should be of such material as to provide interstices between the 110 elements or fiber forming its surface, be

made of fibrous and at least slightly absorbent material, and the fibers themselves should extend at an angle to the length of the film, as shown at 7, 8. These conditions are present in various knitted, netted and woven fabrics, including some which are deliberately woven with diagonal threads, and may be obtained from fabrics of a great variety of forms by cutting the fabric in a direction known as "bias".

The border is preferably placed upon the film body before the apertures 9 are cut. Opposite sides of the border indicated at 10 and 11 may be joined about the edge as at 12 where both sides of the film body are to be protected. There is a distinct advantage in covering both sides where both of the faces of the film are to make contact with reeling or feeding mechanism in thus protecting against scratching of the body of the film as well as against scratching of the photographic image coating.

It will be evident that the film and border will be thoroughly incorporated into each other, whether the softening of the surface of the film be effected after the film is made or be secured by taking the film before it has fully dried. In either case there will be actual entry of the film material into the depressions of the fabric surface between the fibers or where the fibers have been relatively depressed by the law of formation of the fabric.

In each case the protective border may be arranged or selected to yield longitudinally with the film at the same time that it supports against excessive stretch and sets a limit to the permissive stretch well within the safe range of elasticity of the film; so that the border will carry the film away from the danger point in front of the lens in case of sticking or accidental breakage of the film.

Modifications of the construction and method invented by me will occur to those familiar with the manufacture and use of such films, in view of the disclosure of principles made by me herein, and I desire to include within my invention all such modifications and changes as lie within the range and scope of my invention.

Since some forms of film can be softened by application of heat to their surfaces as well as by chemical solvent such as alcohol or ether, I desire to include the application of heat as a solvent: and I consider the ap-

plication of a solvent to the surface as within my invention notwithstanding that additional material is added at the same time, if the application so softens the surface of the body as to blend the added material into that of the body and unite them. In such a case I regard the "body" as made up for effective purposes of the original material plus the added material, whether identical or similar, in so far as the added matter differs from mere solvent.

It will be evident that the film and border provided by my invention will have a higher factor of safety from every standpoint and a longer life than those lacking the border even though the thickness of the film body be reduced somewhat, and that this factor of safety as well as the security of attachment of the border to the body is enhanced by folding the border about the edge and attaching to both sides of the body as in the illustration.

Though I prefer to apply my protective border to the body of the film before the photographic gelatinous coating is applied, the compound film formed by the body and collodion or other photographic coating can be protected by the method and construction described and claimed by me and the border can be applied by softening the photographic coating (or, as is more likely to occur, because of the extreme thinness of the photographic coating, by softening both) and proceeding as hereinbefore described.

Having thus described my invention, what I claim as new and desire to secure by Letters Patent is:—

1. In a device of the character stated, an elastic moving picture film body in combination with a fabric border therefor having the threads of the fabric placed at an angle to the direction of length of the film body.
2. In a device of the character stated, an elastic moving picture film body, in combination with a fabric border therefor, having the fibers of the fabric placed at an angle to the direction of length and width of the film body and the material of the body entering the interstices of the fabric and secured by adhesion of the material of the body to the fabric.

THOMAS T. TUTTLE.
